UNITED STATES PATENT OFFICE.

MAX A. PARTENS, OF BROOKLYN, NEW YORK.

DISPLAY STAND.

Application filed March 9, 1925. Serial No. 14,076.

This invention relates to display stands and particularly to devices of this class adapted for use in displaying predetermined articles on a table or other support and 5 more particularly in the supporting and displaying of printed folders, circulars and the like, said stand being so constructed as to support the pamphlets or circulars in position to facilitate the removal of the same 10 from said stand; a further object being to provide a stand of the class specified, constructed from a single piece of cardboard or similar material cut and scored to permit of the formation of the complete stand and 15 to provide means for locking the stand in operative position; and with these and other objects in view the invention consists in a device of the class and for the purpose specified which is simple in construction, efficient in use and which is constructed as 20 hereinafter described and claimed.

The invention is fully disclosed in the following specification, of which the accompanying drawing forms a part, in which the 25 separate parts of my improvement are designated by suitable reference characters in each of the views, and in which:—

Fig. 1 is a perspective view of a stand made according to my invention and illustrating the method of its use;

Fig. 2 is a central vertical sectional view through the stand shown in Fig. 1; and,

Fig. 3 is a plan view of a blank from which the stand is formed.

In Fig. 3 of the drawing, I have shown at 5 a blank from which my improved stand is formed, said blank being cut from a single piece of cardboard or other suitable material and being fashioned to form a central rectangular body 6 having side wings 7 and 8 foldable upon the scored lines 9 into position at right angles to the body 6 as seen in Figs. 1 and 2 of the drawing. The side wings 7 and 8 are irregular in contour and the upwardly inclined edges 7^a and 8^a thereof form the bottom or leg members of the stand and are in parallel relation when the stand is folded into position, and the back and top edges of the wings 7 and 8 are curved as shown at 10 to provide artistic lines to said side wings.

The side wings 7 and 8 are cut on U-shaped lines 11 to form elongated back wall members 12 and 13 of the separate wings 7 and 8 respectively, said members

being foldable at right angles to the side wings on the score lines 13^a.

Foldably connected with the bottom of the central body 6 on the score line 14 is a bottom member 15 having foldably connected therewith, on the score line 16, a supplemental back wall member 17 provided with a projecting tongue 18, which when the stand is in operative position projects upwardly and backwardly in back of the wall members 12 and 13 to retain the same in operative position. Foldably connected with the supplemental back wall 17 on the score line 19 is a lock member 20, the free edge of which is provided adjacent the side 70 portions thereof with notches 21 adapted to engage one of the walls of the apertures formed by removing the members 12 and 13 from the side wings 7 and 8, said lock member being movable into position at right 75 angles to the supplemental back wall 17 and into engagement with other walls of the apertures of said wings as clearly seen in Fig. 2 of the drawing.

In forming my improved stand from the blank shown in Fig. 3 of the drawing, the parts 15, 17 and 20 are folded backwardly and upwardly, and the side wings 7 and 8 are folded back, and the wall members 12 and 13 thereof inwardly and forwardly, and in this operation the lock member 20 is placed in the apertures of the wings 7 and 8 and the free edge of said member 20 directed upwardly, after which said member is moved downwardly and the walls of the wings 7 and 8 are placed in the notches 21 in this operation and the downward movement of said member continues until the same is in juxtaposition to or resting upon the bottom walls of said apertures as clearly seen in Fig. 2 of the drawing. In this position of the several parts, the tongue 18 projects upwardly beyond the member 20 and rests upon the rear faces of the wall members 12 and 13 to retain them against backward movement.

The stand, folded or constructed in the manner above set out, is now ready for use and printed folders, or circulars or the like, as indicated in dot and dash lines at 22 in Fig. 1 of the drawing, may be placed in the compartment 23 formed between the central body 6 constituting the front wall of the stand and the back walls 12 and 13 including the supplemental back wall 17. It will be 110

noted that the angular arrangement of the leg members of the side wings 7 and 8 support the front wall 6 of the stand in an upwardly and backwardly inclined position and correspondingly support the folders or circulars within the stand exhibiting the upper end portions of the folders or circulars through the open end of the stand above the front wall 6 thereof. It will be understood that any desirable printing matter on the folders or circulars will be exhibited through the stand and the front wall of the stand may have any desired printing matter or other data thereon thus making the entire device not only neat in appearance but of utility, in the performance of the desired function, in supporting the circulars or the like 22 to retain the same always in predetermined position on a table, desk or other support and to facilitate the removal thereof, one by one as desired.

The invention is primarily designed for the purpose of supporting pamphlets, circulars, booklets and the like on a table or other support instead of having such articles loosely positioned on a table or support, which results in the disarrangement thereof as commonly experienced in the removal of one circular, folder or the like from a stack 30 or pile. However, it will be apparent that I am not necessarily limited to the specific use of the invention herein shown and described, as the stand may be used for supporting and displaying articles of any kind or class and further it will be apparent that I am not necessarily limited to the specific details of construction herein shown and described, and various changes therein and modifications thereof may be made, within the scope 40 of the appended claims, without departing from the spirit of my invention or sacrificing its advantages.

Having fully described my invention, what I claim as new and desire to secure by Letters Patent, is:—

1. A stand of the class described fashioned from a single piece of predetermined material to form a front wall, side members projecting below the front wall to form supporting legs, a back wall fashioned from said side walls and spaced from said front wall to form a compartment therebetween and a bottom extending from the front wall and positioned between said side walls, and means for holding and rigidly supporting all of said wall members in operative position.

2. A stand of the class described fashioned from a single piece of predetermined material to form a front wall, side members projecting below the front wall to form supporting legs, a back wall fashioned from said side walls and spaced from said front wall to form a compartment therebetween and a bottom extending from the front wall

and positioned between said side walls, and means for holding and rigidly supporting all of said wall members in operative position, said means being integral with the bottom of the stand.

3. A stand of the class described fashioned from a single piece of predetermined material to form a front wall, side members projecting below the front wall to form supporting legs, a back wall fashioned from said side walls and spaced from said front wall to form a compartment therebetween and a bottom extending from the front wall and positioned between said side walls, and means for holding and rigidly supporting all of said wall members in operative position, said means being integral with the bottom of the stand and being joined therewith by a supplemental back wall.

4. A stand of the class described fashioned from a single piece of predetermined material to form a front wall, side members projecting below the front wall to form supporting legs, a back wall fashioned from said side walls and spaced from said front wall to form a compartment therebetween and a bottom extending from the front wall and positioned between said side walls, means for holding and rigidly supporting all of said wall members in operative position, said means being integral with the bottom of the stand and being joined therewith by a supplemental back wall, and means on said supplemental back wall for retaining the first named back walls in operative position.

5. A stand of the class described comprising a unitary body fashioned from predetermined material and comprising front, side and back wall members, a bottom wall member integral with the front wall member, and means integral with the bottom wall member and cooperating with said side wall members for retaining the stand in operative position, said means including a supplemental back wall member cooperating with the first named back wall members for retaining the same in operative position.

6. A stand of the class described comprising a unitary body fashioned from predetermined material and comprising front, side and back wall members, a bottom wall member integral with the front wall member, means integral with the bottom wall member and cooperating with said side wall members for retaining the stand in operative position, said means including a supplemental back wall member cooperating with the first named back wall members for retaining the same in operative position, and a compartment formed between the front, back and side wall members.

7. A stand of the class described comprising a unitary body fashioned from predetermined material and comprising front, side and back wall members, a bottom wall mem-

ber integral with the front wall member, means integral with the bottom wall member and cooperating with said side wall members for retaining the stand in operative position, said means including a supplemental back wall member cooperating with the first named back wall members for retaining the same in operative position, and a compartment formed between the front, back and side wall members, said compartment being directed upwardly and backwardly.

8. A stand of the class described comprising a unitary body fashioned from predetermined material and comprising front, side and back wall members, a bottom wall member integral with the front wall member, means integral with the bottom wall member and cooperating with said side wall members for retaining the stand in operative position, said means including a supplemental back wall member cooperating with the first named back wall members for retaining the same in operative position, a compartment formed between the front, back and side wall members, said compartment being directed upwardly and backwardly, and the

front wall thereof being of less vertical dimensions than the back walls.

9. A stand of the class described comprising a unitary body fashioned from predetermined material and comprising a front member, side members foldably connected with the front member, a bottom member foldably connected with the front member, back members foldably connected with the side members and extending toward each other and at right angles to said side members in spaced relation to the front member to form a receptacle in the stand between the front, bottom and back members, a supplemental back member foldably connected with the bottom member and engaging the back members to retain the same in position, and a lock part foldably connected with the supplemental back member and adapted to interlocked with the side members for holding all of the parts of the stand in operative position.

In testimony that I claim the foregoing as my invention I have signed my name this sixth day of March 1925.

MAX A. PARTENS.
